DRAIN VALVE

Filed Feb. 23, 1927

Inventor
Robert H. George
Jas. C. Nobensmith
Attorney,

UNITED STATES PATENT OFFICE

ROBERT H. GEORGE, OF BROOKLAWN, NEW JERSEY

DRAIN VALVE

Application filed February 23, 1927. Serial No. 170,116.

My invention relates to drain valves for steam apparatus and the like, and it relates more particularly to that type of automatic drain valve which permits the water of condensation to flow from the steam apparatus, the valve being spring suspended and in use being normally held on its seat, against the tension of the suspending spring, by live steam pressure, the same also serving as a relief valve in the event of any abnormal pressure existing in the working chambers of the steam apparatus which the valve is adapted to drain.

The principal object of my present invention is to provide an improved form of valve of the above mentioned type which will be simple and efficient in its action, and which is so constructed and arranged as to render more certain the necessary freedom of action of the valve member proper, to the end that the same may function properly at all times.

With the foregoing object in view, my invention contemplates certain improved details of construction, as will be hereinafter set forth.

The nature and characteristic features of my invention will be more readily understood from the following description, taken in connection with the accompanying drawings forming part hereof, in which:

Figure 1 is a vertical central sectional view of a drain valve embodying the main features of my present invention, the valve being shown in the raised or elevated position assumed when the live steam supply is shut off;

Fig. 2 is a transverse section thereof, taken on the line 2—2 of Fig. 1;

Fig. 3 is a horizontal section, taken approximately on the line 3—3 of Fig. 1;

Fig. 4 is a horizontal section, taken approximately on the line 4—4 of Fig. 2; and

Fig. 5 is a side elevation of the valve member proper.

Referring to the drawings, in the particular embodiment of my invention therein shown, 6 is an integral cup-shaped casing having an internal chamber 7, the bottom 8 of which is preferably frusto-conical in shape to form a seat for the valve member 9, which is mounted in the chamber 7 and has its under

portion 10 also preferably frusto-conical in shape, complementary to the bottom 8 of the chamber 7.

The top of the chamber 7 is closed by means of a bonnet 11, which is preferably threaded in the upper end of the casing 6, a packing washer 12 being provided and interposed to seal the joint between the bonnet 11 and the casing 6.

A bolt 13 is threaded in the top of the bonnet 11, extending therethrough and being provided at its inner end with an eye 14 for the attachment of one end of a spring 15, which is provided for supporting the valve member 9 in the manner to be hereinafter more fully set forth.

The top of the bonnet 11 is provided with a stuffing box 16, containing suitable packing 17, which surrounds the bolt 13 and serves to prevent leakage of the live steam where the bolt 13 passes through the top of the bonnet 11. A gland 18 is threaded into the stuffing box 16, serving to confine and compress the packing 17 therein.

The lower end of the spring 15 engages the eye portion 19 of a pin 20. The pin 20 has an enlarged head 21, which is confined within the body of the valve member 9 by means of a sleeve 22, which is secured in a complementary recess in the lower portion of the valve member 9, either by a forced fit or by threading the same therein. The sleeve 22, while confining the head 21 of the pin 20 within the body portion of the valve member 9, will at the same time permit rotative movement of the valve member with respect to the pin 20, and consequently with respect to the spring 15, thereby permitting the valve member to rotate within the chamber 7 of the casing 6, to insure even wear of the coating surfaces of the valve member and seat.

The body of the valve member 9 is preferably made of a diameter slightly smaller than that of the chamber 7 of the casing 6. Extending upwardly from the body portion of the valve member 9 is a cage-like structure comprising a plurality of arms 23, extending upwardly from the body portion of the valve member and connected at their upper ends by an annulus 24.

The cage-like structure, comprising the arms 23 and annulus 24, is of such external diameter as to make a sliding fit with the surface of chamber 7. The cage-like structure 5 provided above the valve member 9 extends upwardly a distance sufficient for the same to contact with the lower internal portion of the bonnet 11, and thus limit the upward movement of the valve member, so as to locate the 10 same properly in its uppermost position.

Extending externally from the side wall of the casing 6 is a threaded nipple 25, having a port or passageway 26 which communicates with the upper portion of the valve 15 chamber (see Fig. 2) above the body portion of the valve member. The connection nipple 25, in the use of the device, is adapted to be connected by suitable piping (not shown) to the steam chest or other similar portion of 20 the steam engine or other apparatus in connection with which the valve is used.

Extending externally from the lower portion of the casing 6 are one or more connection nipples 27, each provided with a port 25 or passageway 28, extending to the frusto-conical seat portion 8 of the valve chamber 7. The ports or passageways 28 have no upward extensions whereby water could accumulate therein and be frozen, and thus close 30 the ports.

The ports 28 are adapted to be closed by the valve member 9 when the same is in its lowermost or seated position. The connection nipples 27 are adapted to be connected by means 35 of suitable piping (not shown) to the respective ends of the steam cylinder of the engine, or the corresponding portions of similar apparatus.

It should be noted that, in the embodiment 40 of my invention shown in the drawings, there are provided two of the connection nipples 27, oppositely disposed in alignment with each other, but it will be readily understood that in some instances, for use in connection 45 with other kinds of apparatus, a greater or smaller number of such connection nipples may be provided if desired, without departing from the spirit of my invention, as will be readily apparent to those skilled in the 50 art.

Projecting downwardly from the bottom of the casing 6 is a connection nipple 29, having an internal passageway 30 which extends from the bottom of the internal chamber 7. The nipple 29 is adapted to be connected to a 55 drain pipe for carrying away the water of condensation which is permitted to pass through the device.

The operation of the device may now be 60 explained. When the steam engine, or other apparatus in connection with which the device is used, is not in operation, and the live steam supply is cut off, the valve member 9 will be held in the raised or elevated position 65 by means of the spring 15, as shown in Figs.

1 and 2 of the drawings, the outwardly extending cage-like portion of the valve member 9 serving to limit the upward movement thereof by contacting with the lower internal portion of the bonnet 11.

When the valve member is in the raised position as above set forth, any water of condensation which may collect in the steam chest will pass, by means of the piping (not shown) which extends from the steam chest 70 of the engine, to the connection nipple 25, and will be permitted to pass above the body portion of the valve member 9, and thence through the clearance space provided between the sides of the body portion of the valve member and the side walls of the chamber 7, after which the same will pass through the passageway 30 of the connection nipple 29 to the drain. Also, when the valve member 9 is in this position, any water of condensation 80 which may collect in the respective ends of the steam cylinder of the engine will be permitted to pass through the piping extending therefrom to the connection nipple 27, thence through the ports 28 and through the passageway 30 to the drain.

When, however, the live steam pressure is turned on in the engine, the initial flow of the steam through the device will cause the valve member 9 to be carried downward and seated upon the frusto-conical seat 8, thereby closing the ports 28 as well as the passageway 30 which extends to the drain.

Subsequently, when the live steam supply is shut off to stop the engine, the greater pressure which will exist for a short time in the ends of the engine cylinder will cause the valve member 9 to be positively lifted from its seat, and to be held thereafter in the raised position by the spring 15.

When the valve member 9 is in the lower or closed position, the ports 28 will be closed against the normal pressures existing in the respective ends of the engine cylinder, but should any condensation water accumulate in the cylinder of the engine, the same will be forced through the piping and will cause the valve member 9 to be raised sufficiently to permit the same to escape through the passageway 30 and thence to the drain, after 115 which the valve member will again be seated and maintained on its seat by the live steam pressure on the upper surfaces thereof.

It should be noted that, by reason of the provision of the cage-like portion of the valve member, which extends above the body portion thereof and is of such diameter as to provide a sliding fit within the chamber 7 of the casing 6, the valve member will be guided in its up and down movements, and tilting of the valve, which might cause the same to jam within the casing and thereby fail to function properly, will be effectively prevented. The valve member will preferably be so located with respect to the passageway 120 125 130

26 of the connection nipple 25 as to permit the live steam to pass therefrom directly into the chamber 7 above the body portion of the valve member, and thus insure the proper closing of the ports 28 and drain passageway 5 30 when the live steam is turned on in the portion of the apparatus to which the connection nipple 25 is piped.

Having thus described the nature and characteristic features of my invention, what I 10 claim as new and desire to secure by Letters Patent, is:

1. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, 15 said valve member having a cage-like structure above the body portion comprising a plurality of arms extending upwardly from the body portion of the valve member and an annulus connecting the upper ends of said arms, said cage-like structure being of such external diameter as to form a sliding fit in the internal chamber, the body portion of the valve member being of a diameter slightly less than that of the internal chamber, a 20 spring adapted to hold said valve member in its raised position, a pipe connection member extending from the side wall of the casing and having a port extending to the internal chamber, a plurality of pipe connection members extending from the lower portion of the casing having ports extending to the valve seat, and the casing having a downwardly extending passageway communicating with the interior of the casing at the bottom of the valve seat.

2. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external diameter as to form a sliding fit in the internal chamber, the body portion of the valve member being of a diameter slightly less than that of the internal chamber, a spring adapted to hold said valve member in its raised position, a pipe connection member having a port extending to the internal chamber, a pipe connection member having a port extending to the valve seat, and the casing having a downwardly extending passageway communicating with the interior of the casing at the bottom of the valve seat.

3. An automatic drain and relief valve comprising a cup-shaped casing having an internal chamber the bottom of which is shaped

to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external 70 diameter as to form a sliding fit in the internal chamber, the body portion of the valve member being of a diameter slightly less than that of the internal chamber, a spring adapted to hold said valve member in its 75 raised position, a pipe connection member extending from the side wall of the casing and having a port extending to the internal chamber, a plurality of pipe connection members extending from the lower portion of the casing having ports extending to the valve seat, and the casing having a downwardly extending passageway communicating with the interior of the casing at the bottom of the valve seat.

4. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external 90 diameter as to form a sliding fit in the internal chamber, the body portion of the valve member being of a diameter slightly less than that of the internal chamber, a spring adapted to hold said valve member in its raised position, a pipe connection member having a port extending to the internal chamber, a pipe connection member having a port extending to the valve seat, and the casing having a downwardly extending passageway 95 communicating with the interior of the casing at the bottom of the valve seat.

5. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such 100 diameter as to form a sliding fit in the internal chamber, the body portion of the valve member being of a diameter slightly less than that of the internal chamber, a bonnet mounted in the upper portion of the casing forming a closure for the top of the chamber, a spring adapted to hold said valve member in its 105 raised position, a pipe connection member having a port extending to the internal chamber, a pipe connection member having a port extending to the valve seat, and the casing having a downwardly extending passageway 110 communicating with the interior of the casing at the bottom of the valve seat.

6. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such 115 diameter as to form a sliding fit in the internal chamber, the body portion of the valve member being of a diameter slightly less than that of the internal chamber, a bonnet mounted in the upper portion of the casing forming a closure for the top of the chamber, a spring adapted to hold said valve member in its 120 raised position, a pipe connection member having a port extending to the internal chamber, a pipe connection member having a port extending to the valve seat, and the casing having a downwardly extending passageway 125 communicating with the interior of the casing at the bottom of the valve seat.

external diameter as to form a sliding fit in the internal chamber, the body portion of the valve member being of a diameter slightly less than that of the internal chamber, a bonnet mounted in the upper portion of the casing forming a closure for the top of the chamber, a spring adapted to hold said valve member in its raised position, a pipe connection member extending from the side wall of the casing and having a port extending to the internal chamber, a plurality of pipe connection members extending from the lower portion of the casing having ports extending to the valve seat, and the casing having a downwardly extending passageway communicating with the interior of the casing at the bottom of the valve seat.

6. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external diameter as to form a sliding fit in the internal chamber, the body portion of the valve member being of a diameter slightly less than that of the internal chamber, a bonnet mounted in the upper portion of the casing forming a closure for the top of the chamber, a spring adapted to hold said valve member in its raised position, means for adjustably connecting one end of said spring to the bonnet, means for rotatively connecting the other end of said spring to the valve member, a pipe connection member having a port extending to the internal chamber, a pipe connection member having a port passing directly to the valve seat without upward extensions, and the casing having a downwardly extending passageway communicating with the interior of the casing at the bottom of the valve seat.

50 7. An automatic drain and relief valve comprising a cup-shaped casing having an internal chamber the bottom of which is shaped to form a seat, a valve member mounted in said chamber having its lower surface shaped complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external diameter as to form a sliding fit in the internal chamber, the body portion of the valve member being of a diameter slightly

less than that of the internal chamber, a bonnet mounted in the upper portion of the casing forming a closure for the top of the chamber, a spring adapted to hold said valve member in its raised position, means for adjustably connecting one end of said spring to the bonnet, means for rotatively connecting the other end of said spring to the valve member, a pipe connection member on the side wall of the casing and having a port extending to the internal chamber, a plurality of pipe connection members on the lower portion of the casing having ports passing directly to the valve seat without upward extensions, and the casing having a downwardly extending passageway communicating with the interior of the casing at the bottom of the valve seat.

8. An automatic drain and relief valve comprising a cup-shaped casing having an internal chamber the bottom of which is frusto-conical in shape to form a seat, a valve member mounted in said chamber having its lower surface frusto-conical in shape complementary to the bottom of the chamber and adapted to be seated thereon, said valve member having a cage-like structure above the body portion comprising a plurality of arms extending upwardly from the body portion of the valve member and an annulus connecting the upper ends of said arms, said cage-like structure being of such external diameter as to form a sliding fit in the internal chamber, the body portion of the valve member being of a diameter slightly less than that of the internal chamber, a bonnet mounted in the upper portion of the casing forming a closure for the top of the chamber, a spring adapted to hold said valve member in its raised position, means for adjustably connecting one end of said spring to the bonnet, means for rotatively connecting the other end of said spring to the valve member, a pipe connection member extending from the side wall of the casing and having a port extending to the internal chamber, a plurality of pipe connection members extending from the lower portion of the casing having ports passing directly to the valve seat without upward extensions, and the casing having a downwardly extending passageway communicating with the interior of the casing at the bottom of the valve seat.

9. In an automatic drain valve of the type in which the valve member is spring suspended within a casing having an internal cylindrical surface, a valve member having a cage-like structure above the body portion comprising a plurality of arms extending upwardly from the body portion of the valve member and an annulus connecting the upper ends of said arms, the external surfaces of said arms and annulus being complementary to the internal surface of the casing, said

cage like structure being of such external diameter as to form a sliding fit in the casing, and the body portion of the valve member being of a slightly smaller diameter.

- 5 10. In an automatic drain valve of the type in which the valve member is spring suspended within a casing having an internal cylindrical surface, a valve member having its lower surface frusto-conical in shape and 10 having a cage-like structure above the body portion comprising a plurality of arms extending upwardly from the body portion of the valve member and an annulus connecting the upper ends of said arms, the external surfaces of said arms and annulus being complementary to the internal surface of the casing, 15 said cage-like structure being of such external diameter as to form a sliding fit in the casing, and the body portion of the valve member 20 being of a slightly smaller diameter.

In testimony whereof, I have hereunto signed my name.

ROBERT H. GEORGE.
